Attorney.

UNITED STATES PATENT OFFICE.

WILLIAM C. BLUNDELL, OF LOS ANGELES, CALIFORNIA.

LOW-WATER ALARM.

1,259,720.

Specification of Letters Patent. Patented Mar. 19, 1918.

Application filed March 2, 1917. Serial No. 153,532.

To all whom it may concern:

Be it known that I, WILLIAM C. BLUNDELL, a citizen of the United States, residing at Los Angeles, in the county of Los Angeles 5 and State of California, have invented a new and useful Improvement in Low-Water Alarms, of which the following is a specification.

My invention relates to low water alarms 10 and signals for indicating the low water stage in steam boilers and the like, and has for its object the provision of a device for this purpose which may be readily attached to the different types of boilers and 15 which embodies simplicity of structure and economy.

A further object of this invention is to provide an alarm for indicating the low water stage in locomotive boilers particu- 20 larly, but which may be also used for stationary boilers.

A further object is to provide a device which includes an expansion element connected with both the water and steam com- 25 parts of the boiler which may be heated by the steam and expanded for operating the signal when the water in the boiler reaches the danger stage, and which will be readily cooled when the water supply has been re- 30 plenished.

I am aware that the use of an expansion tube in a device of this kind is not in itself new and that other devices for this purpose have been invented, patented and used for 35 a number of years but I am not aware that any device has heretofore been used or known which embodies the improvements set forth in this application. Other objects may appear in the following description.

40 In the consideration of this invention reference is had to a former invention of mine relating to water indicating means for boilers as disclosed in Letters Patent granted to me on April 10, 1917, Patent Number 1,221,963; and also to another invention disclosed in an application for patent filed by me on Sept. 5, 1916, Serial No. 120,860.

50 Referring to the drawings, Figure 1 is a front elevation of my alarm device showing a form for use in connection with locomotive boilers. Fig. 2 is a plan of the same, Fig. 3 is a right hand end elevation of the same, and Fig. 4 is a left hand elevation of Fig. 1 showing a modified form of device.

55 Similar characters of reference are used

in the specification and in the several views of the drawings for indicating similar and like parts.

In the form of device shown in Figs. 1, 2, and 3 I provide a water column 1 which has 60 extensions 2 and 3 formed thereon near the top and bottom, respectively. The interior of the water column 1 is subdivided into two compartments, the upper compartment 4 being the shorter of the two and being 65 separated from the lower compartment 5 by means of the partition 6. The upper compartment 4 is connected with the steam compartment of the boiler 7 by means of a pipe 8 and an elbow 9, and a valve 10 is connected with the pipe 8 intermediate of the water column 1 and the boiler 7 so that the steam supply from the boiler may be regulated or shut off as desired.

The lower compartment 5 of the water 75 column is connected with the water compartment of the boiler 7 by means of a pipe 11, an elbow 12 and the pipe 13, a dripcock 14 being connected with the pipe 11 and the elbow 12 for draining the water therefrom, 80 and a valve 15 being connected with the elbow 12 and the pipe 13 for regulating or shutting off the water from the water column. The extension 3 occupies a position 85 on the water column 1 which is slightly above the low water stage in the boiler and a passage 16 is formed therein which communicates with the water chamber 5 of the water column.

One end of an expansion tube 17 is thread- 90 ed or otherwise suitably secured in the passage 16 of the extension 3 so that the interior of the tube will communicate with the chamber 5 in the water column. The outer end of the tube 17 is attached to a T 18 95 which is closed at the outer end by means of a plug 19.

The extension 2 of the water column has a passage 20 which communicates with the steam chamber 4 and is connected with a 100 pipe 21 which terminates at its outer end in a T 22. A whistle 23 is attached by means of the base 24 and a pipe 25 to the T 22, and a flexible tube 26 connects the T 18 on the expansion tube 17 with the T 22 on the 105 pipe 21. Suitable unions 27 are provided on the ends of the flexible tube 26 for facilitating the attachment of the tube to the T's. Thus, an uninterrupted passage for the water and steam is provided for con- 110

necting the chamber 4, the tube 26, the tube 17, and the chamber 5 and the tube 25 in which the water from the boiler may rise to a height to correspond to that in the boiler, 5 and when the low stage of water is reached the steam may descend through the chamber 4 and the tube 26 into the expansion tube 17, and thus displace the water for expending the tube 17.

10 The plug 19 on the end of the T 18 is slotted to receive and serves to pivotally hold a vertically disposed lever 28. The lower end of this lever is pivotally attached to a horizontally disposed rod 29 which is 15 rigidly attached at the other end by means of nuts 31 to a depending lug 30 formed on the outer end of the extension 3. The upper end of the lever 28 is pivotally attached to the outer end of a rod 32 and the other end 20 of this rod is similarly attached to the lower end of the whistle lever 33 which operates the valve stem 34 of the whistle, in the usual manner.

The leverage of the lever 28 is such that 25 a very slight movement of the lower end, caused by the expansion of the tube 17, will effect a sufficient movement of the upper end of the lever to operate the whistle 23. It will be observed that when this device 30 is attached to the boiler in the manner shown, in the event that the water in the boiler is above the level of the pipe 8 the chambers 4 and 5 in the water column, the tubes 17 and 26 and the pipes 21 and 25 35 will be filled with water and it will be impossible for the steam to gain access to the whistle valve 24 but when the water descends below the level of the pipe 21, the steam will enter this pipe and be admitted 40 to the pipe 25 into contact with the whistle valve. In such case the tube 17 and a portion of the tube 26 will be filled with water as the stage of the water in the boiler in such event, will be above the low water 45 stage. When, however, the low water stage is reached the steam will enter the tube 17 through the tube 28 and the T 18, thus replacing the water, and heating the tube 17 and causing it to expand. It is obvious 50 that the expansion of the tube 17 will move the plug 19 and the T 18 outwardly from the water column but the lower end of the lever 28, in such case, is held against movement by the rod 29 which is stationary, and 55 the upper end of the lever 28 is moved outwardly and serves to operate the whistle valve stem 34 by means of the lever 33, thus admitting the steam to the whistle and sounding an alarm.

60 By reference to Fig. 4 it will be observed that the water column 1 may be dispensed with in some cases and steam pipes 8 and 13 which are connected with the boiler may be attached directly to the pipe 21 and the 65 tube 17. In such case a lug 30 which is

similar to the lug on the extension 3 may be provided on the elbow 35 attached to the pipe 13 in order to provide means for attaching the rod 29 thereto.

A valuable feature of this invention consists in the connection of the tube 17 with both the water and steam compartments of the boiler. Experience has proven that should this expansion tube be connected only with the steam compartment, while it 75 will heat rapidly when the steam is admitted into it, it will not cool rapidly enough and the alarm will continue to sound for some time after the water has been replenished. In my improved device 80 however as soon as the water in the boiler rises so that it may enter the tube 17, this tube will be cooled immediately to a temperature sufficient to contract the tube and shut off the steam supply from the whistle. 85

It should be understood that I do not limit myself to the use of a whistle or to an alarm, as it obviously is possible to provide a mechanical signal which may be operated by the steam pressure; nor do I limit myself 90 to the exact form of the other elements shown, for it is conceived to be possible to modify the structure somewhat to meet different conditions obtaining with different types of boilers.

Having thus described my invention what I claim is:

1. A low water alarm for steam boilers including an expansible tube connected at opposite extremities with the steam and water portions of the boiler and positioned wholly between the high and low water levels of the boiler to permit the circulation of steam and water therethrough, and signaling means connected with and arranged 100 for operation by the expansion of said tube.

2. A low water alarm for steam boilers comprising an expansible tube connected with the steam and water compartments of the boiler and positioned between the high 110 and low water levels thereof, signal means attached to and arranged for operation by the expansion of said tube, and operating means for said signal.

3. A low water alarm for steam boilers 115 comprising a water and a steam connection with the boiler at the low and high water levels, respectively, a signal attached to said steam connection, an expansible tube connected with said water connection and with 120 said signal and arranged to permit the circulation of the steam and water therethrough, and means fixed to the end of said tube for operating said signal.

4. A low water alarm for steam boilers 125 comprising a horizontally extended steam and water connection from the boiler at the high and low water levels, respectively, a horizontally disposed expansion tube connected with said water connection, a signal 130

- connected with said steam connection, and a flexible connection for affording communication between said tube and said signal.
5. A low water alarm for steam boilers comprising separate water and steam connections from the boiler at the low and high water levels, respectively, an expansion tube for affording communication therebetween and arranged for being completely filled 10 with water and steam according to the stage of the water in the boiler, and steam actuated signaling means connected with said steam connection and with said tube for operation coincidently with and by the expansion 15 and contraction of said tube.
6. A low water alarm for steam boilers comprising steam and water connections extending from the high and low water levels of the boiler, a water and steam column 20 connected with and supported therebetween and having disconnected steam and water compartments, an expansion tube in communication with the water compartment therein, a steam pipe communicating with the 25 steam compartment therein, a connection between the outer extremity of said tube and said steam connection, a signal in communication with said steam connection, and signal actuating means operable by the expansion and contraction of said tube.
7. A low water alarm for steam boilers comprising separate steam and water chambers connected, respectively, with the steam and water compartments of the boiler, an 30 expansion tube communicating with said water compartment and supported substantially in the plane of the low water level, a steam connection leading from said steam chamber and communicating with the outer 35 extremity of said tube, a steam actuated signal connected with said steam connection intermediate of said steam chamber and said tube, and signal operating means supported on and operable by the expansion of 40 said tube.
- 45

8. A low water alarm for steam boilers comprising a rigid support having separate water and steam chambers therein connected, respectively, with the water and steam portions of the boiler, an expansion tube 50 supported thereon and disposed in the plane of the low water level, a steam connection between said tube and said steam chamber, a signal communicating with said steam connection and positioned intermediate of 55 said tube and said steam chamber, an operating member rigidly held at one end on said support, attached to said tube and also attached to said signal, for admitting steam to the signal coincidently with the expansion 60 of said tube.

9. A low water alarm for steam boilers comprising a horizontally disposed expansion tube supported substantially in the plane of the low water level of the boiler 65 and communicating at opposite extremities with the steam and water portions of the boiler, a signal communicating with the steam compartment thereof, and operating means for admitting steam to the signal 70 coincidently with the expansion of said tube.

10. A low water alarm for steam boilers comprising a continuous connection mounted exterior of the boiler for affording communication between the steam and water 75 portions thereof and including a horizontally disposed expansion tube capable of expansion and contraction, respectively, when filled with steam or water from the boiler, a signal communicating with said 80 connection, and means for operating said signal when said tube is expanded by the presence of steam therein.

Signed at Los Angeles, in the county of Los Angeles, State of California, this 2nd 85 day of January, 1917.
